UNITED STATES PATENT OFFICE.

JAMES THOMAS THADDEUS ELLIS, OF SOUTHERN PINES, NORTH CAROLINA.

TRAMWAY-CARRIAGE.

1,270,131.

Specification of Letters Patent. Patented June 18, 1918.

Application filed October 29, 1917. Serial No. 199,179.

To all whom it may concern:

Be it known that I, JAMES THOMAS THADDEUS ELLIS, a citizen of the United States, residing at Southern Pines, in the county of 5 Moore and State of North Carolina, have invented new and useful Improvements in Tramway-Carriages, of which the following is a specification.

This invention relates to new and useful 10 improvements in a tramway-carriage or traveler and the principal object of the invention is to provide means for moving the carriage and to raise and lower the load by a pair of cables thus omitting the third cable 15 usually used in devices of this nature.

Another object of the invention is to provide electrically operated means for gripping the cables to prevent movement of the carriage and to hold the load in raised position.

The invention also consists in certain other features of construction and in the combination and arrangement of the several parts, to be hereinafter fully described, illustrated 25 in the accompanying drawings and specifically pointed out in the appended claim.

In describing my invention in detail, reference will be had to the accompanying drawings wherein like characters denote like 30 or corresponding parts throughout the several views, and in which:—

Figure 1 is a longitudinal section of the device.

Fig. 2 is an end view thereof.

Fig. 3 is a horizontal section on the line 35 3—3 of Fig. 1.

Fig. 4 is a section on line 4—4 of Fig. 1.

As shown in the drawings the carriage is formed of a pair of plates 1 spaced apart 40 and suitably connected together by the bolts 2 and the sleeves 3. Between these plates and adjacent the upper end thereof are located the grooved wheels 4 for supporting the device on the cable A. These wheels are 45 preferably provided with ball bearings and rotate on the axles 5. 6 represents a similar pair of wheels located adjacent the lower edge of the device over which the lifting cable B passes. These wheels are mounted

50 on the axles 7 and are also provided with ball bearings. The top and bottom of the carriage are formed of U-shaped plates 8 and 9, these plates being secured to the plates 1 in any suitable manner. 10 indicates a stationary jaw connected to the plates 1 in any desired manner and located im-

mediately above the cable A. 11 indicates the movable jaw coöperating with the stationary jaw 10 to grip the cable A. This movable jaw has a reduced lower end sliding in guides 12 carried by the plates, said guides being provided with rollers 12' with which the back of the reduced part of the movable jaw engages. The front of this part is provided with the teeth 12" with which engages the teeth on the segmental lever 13, pivoted at 14 to the plates. The other end of this lever is pivoted to the armature 15 of magnet 16 which is pivoted at 17 to the plates. Current is carried to 70 this member from the wire C by means of the trolley wheel 18 and the wire 19 connecting said wheel with the magnet. A similar arrangement of parts is provided for the cable B, said parts consisting of the 75 stationary and movable jaws 20, guide 21, segmental lever 22 and the magnet and its armature 23. Current is supplied to the magnet 23 from the wire D by means of the trolley wheel 24 and the wire 25. The wires 80 19 and 25 pass through suitable insulating plugs 26 carried by the top 8.

The carriage may be moved toward the left by any suitable means. For instance a cable A may be connected to this end of the 85 carriage. As this is well known I have not shown this means on the drawing.

When the carriage has been moved to the desired position to receive the load, current is passed through wire C to the magnet 16. 90 This will cause the armature 15 to move so as to rock the lever 13 on its pivot and thus raise the jaw 11 to grip the cable A and thus hold the carriage against movement on said cable. The hoisting drum is then started so as to wind up the cable B to lift the load. After the same is raised to the proper height current is sent through the wire D and so into the magnet 23. Thus the movement of the armature will rock the lever 22 to cause 100 the jaws to grip the cable B to hold the load in raised position. The magnet 16 is then deenergized to release the cable A and the carriage is then pulled to the desired position. It will thus be seen that just two 105 cables are necessary as the third cable may be omitted.

It is thought from the foregoing description that the advantages and novel features of my invention will be readily apparent.

I desire it to be understood that I may make slight changes in the construction and

in the combination and arrangement of the several parts, provided that such changes fall within the scope of the appended claim.

What I claim is:—

- 5 A device of the class described comprising a frame, supporting wheels carried thereby for engaging the supporting cable, hoisting wheels thereon engaging the hoisting cable, gripping means for each cable, each includ-

ing stationary and movable jaws, teeth on 10 said movable jaw, a segmental lever having teeth thereon engaging with said teeth, a magnet, an armature therefor connected with the lever, and a trolley connected with each magnet.

15

In testimony whereof I affix my signature.

JAMES THOMAS THADDEUS ELLIS.
